DESIGN FOR A NOVELTY PIN

Samuel J. Blume, Brooklyn, N. Y.

Application May 12, 1942, Serial No. 106,876

Term of patent 3½ years

To all whom it may concern:

Be it known that I, Samuel J. Blume, a citizen of the United States, residing at 68 East 19th Street, Brooklyn, New York city, in the county of Kings, State of New York, have invented a new, original, and ornamental Design for a Novelty Pin, of which the following is a specification, reference being had to the accompanying drawing, forming part thereof.

Fig. 1 is a front view in elevation of a novelty pin, showing my new design.

Fig. 2 is a side view thereof.

I claim:

The ornamental design for a novelty pin, substantially as shown.

SAMUEL J. BLUME.
